TONE-DEVELOPING UNIT.

Application filed July 6, 1925. Serial No. 41,625.

This invention relates to a tone developing unit, particularly designed for use in phonographic and radio reproduction of sound.

5 The object of the invention is, in general, to provide a novel and improved tone developing unit, particularly adapted for use as amplifying and transmitting or conducting apparatus for conveying reproduced sounds and amplifying them without the production of harshness of tone and the confusion or blurring experienced with all prior apparatus of this character of which I am aware.

15 The invention has for a further object to provide sound reproducing apparatus by which the tone, quality, and power of the reproduced sound is improved, so that the sound is reproduced in a perfectly natural 20 tone and with the full power and melody of the original voice or voices, or instrument or instruments, whose sound is being reproduced, and to overcome everything foreign to the reproduction of perfect music, 25 vocal or instrumental, and in general to reproduce with original volume, melody and power, every detail of the original sound being produced. Apparatus embodying the 30 present invention is particularly useful in connection with the reproduction of voice and music by radio receivers, and particularly in loud speaker units thus eliminating, or at least reducing to a minimum, harshness and indistinctness which have characterized the apparatus of this character heretofore employed.

With these objects, and such other objects, in view as may hereinafter appear, the invention consists in the tone developing unit 40 hereinafter described, and particularly defined in the claims at the end of this specification.

In the drawing illustrating the preferred embodiment of the invention, Figure 1 is a 45 vertical sectional view of the improved unit illustrating its use in connection with a radio receiving unit; Fig. 2 is a side elevation with portions in dotted lines illustrating the embodiment of the unit in a phonograph and 50 its manner of use in connection therewith; Fig. 3 is a front elevation of the unit, viewed from the mouth thereof; and Fig. 4 is a sectional view on line 4-4 of Fig. 2.

Referring to the drawing, the present tone developing unit is provided with two sound 55 chambers each of trigonal cross-section, comprising preferably a vertical sound chamber 10, and a horizontal sound chamber 12 combined as a unit, and provision is made at the connection between these chambers to 60 cause sound waves passing from the vertical chamber into the horizontal chamber to be delivered in their natural condition and with fully developed tone, and without causing confusion or blurring of the different components of the waves, an objectionable phenomenon occurring with all prior types of sound reproducing apparatus of which I am aware, and which is readily apparent to the 65 expert in the indistinctness and the failure to faithfully reproduce both the fundamental and over-tones in their proper relation to one another.

I have by experiment found it desirable to form the vertical chamber 10 into which the sound waves are delivered, either from the diaphragm of the usual or any preferred form of loud speaker unit 14, or from the tone arm 15 of the usual phonograph 16, or from any other source, of the special shape 75 illustrated in Figs. 1 and 4. As therein shown, the upper portion of the chamber is rectangular in transverse section, and of a relatively small dimension, to provide in effect a throat 18 into which the waves are 80 delivered by the diaphragm. The remaining portion of the vertical chamber is preferably formed in the shape of a frustum of a pyramid, thus being of trigonal longitudinal cross-section. The lower, and larger, end 85 terminates at one end of the second sound chamber 12, as shown in Fig. 1. The second sound chamber 12 is also rectangular in transverse cross-section, and the upper wall 19 thereof is preferably inclined at an angle, 90 depending upon the volume of amplification desired, producing a trigonal longitudinal cross-section. The chamber 12 is of constant width from end to end and is provided with an open mouth 20 through which the amplified tones or sounds emerge. The opening 21 through which communication is afforded 95 from the bottom of the vertical chamber 10 to the throat 22 of the second sound chamber and which I designate an analyzing tone, 100 is formed to provide in effect a series of

openings 23, 24, 25, of widths progressively increasing from the top to the bottom of the throat 22 of the second sound chamber 12, and in practice I have produced excellent results with this tone portal 21 of the construction and general shape illustrated in Figs. 3 and 4, in which the vertical wall 26 of the vertical sound chamber 10 is extended downwardly across the throat 22 of the second sound chamber 12, and the tone portal 21 is cut therein in the form illustrated by Figs. 3 and 4, providing a series of projecting portions, impingements or corner pieces 30, 31, 32, which appear to play an important part in the successful operation of the tone developing unit. I have found that for the ordinary size of amplifier used in connection with the ordinary loud speaker unit for radio reception, or for an amplifier for the ordinary phonograph, that the portal, however it is formed, should provide a centrally arranged series of connected openings 23, 24, 25, with the depth of the openings gradually decreasing from the top to the bottom, and width of the openings gradually increasing. The exact proportions may be varied within limits, but I have found that the relative areas of these openings should be in approximately the proportion illustrated in Figs. 3 and 4. This provides a partition in the throat 22 that impinges on the sides thereof providing a tone portal as high as the throat centrally but as a whole having a rough trigonal cross-section.

In the operation of the sound amplifying or tone developing unit, either when used in connection with the usual diaphragm of a loud speaker unit 14, one of which is conventionally shown in Fig. 1, or when used in connection with the tone arm 15 and diaphragm of the ordinary phonograph (see Fig. 2), the peculiarly shaped tone portal 21 in combination with the two combined tone chambers 10, 12, one arranged to deliver through the portal 21 into the throat of the second, causes the fundamental sound waves, I believe, to escape unrestricted through the central opening of the portal, whereas the over-tones are, so to speak, restricted and prevented from intermingling with the fundamentals in an objectionable manner by the projecting corner pieces 30, 31, 32, comprising the walls of the portal. As to why this peculiarly shaped tone portal 21 should operate in this manner, I can only state that experiment has proven that it will overcome the objectionable indistinctness and harshness so apparent to an expert, resulting from the use of prior constructions of sound amplifying apparatus, either with radio receiving apparatus, or with phonographs.

The sound chambers may be made of any material found suitable for the purpose, but I prefer employing fine grained spruce because of its particular resonance, and while

the general shape of these chambers as illustrated in the drawings has been found to give very satisfactory results, I believe that some variations could be used without disadvantage if the trigonal form is preserved.

In the use of the instrument in reproducing sound and particularly music from diaphragms, it has been found that the weak over-tones reproduced by the diaphragms may be strengthened by the present apparatus so that the tone is actually developed into a fullness and completeness of tone equal to and in some instances exceeding that of the original sound or music being reproduced.

While the preferred embodiment of the invention has been illustrated and described, it will be understood that the invention may be embodied in other forms within the scope of the following claims.

Having thus described the invention, what is claimed is:

1. Tone developing apparatus comprising two sound chambers, each provided with a relatively narrow throat portion, and with a wider portion, located so that one chamber is in communication with the throat portion of the other chamber, a tone portal connecting said chambers restricted by side impingements within the opening between said chambers, and a mouth at the enlarged end of the second chamber through which the amplified sounds emerge.

2. Tone developing apparatus comprising two sound chambers, each provided with a throat portion of relatively small sectional dimension, and an end portion of greater sectional dimension, and with the throat portion of one chamber located immediately adjacent the enlarged portion of the other chamber, and a flat partition of fine grained wood located in the opening at the connection between said throat and enlarged portions of said chambers, provided with a central tone portal.

3. Tone developing apparatus comprising two sound chambers provided with throat portions and enlarged end portions, and combined as a unit, and having the throat portion of the second chamber positioned at the enlarged end of the first chamber, and means for connecting said chamber through a tone portal of rough trigonal section and of less area than the throat of the second chamber.

4. Tone developing apparatus comprising a vertical sound chamber provided with a throat at the upper end thereof, a horizontal sound chamber provided with a throat communicating with the lower portion of the vertical sound chamber, the lower end of one of the vertical walls of said vertical sound chamber being extended across the throat of said second sound chamber to the opposite sides thereof and provided with a central tone portal.

5. Tone developing apparatus comprising

two tone developing chambers each of sectional dimensions progressively increasing from one end thereof toward the other end, and means providing a restricted tone portal 5 between the enlarged end of one chamber and the smaller end of the second chamber for the purpose specified, said portal being centrally substantially the height of the opening at the smaller end of the second 10 chamber and decreasing progressively in height from its center toward each side of said opening.

6. Tone developing apparatus comprising a duplex tone chamber each part being of 15 trigonal longitudinal cross-section arranged at right angles to each other with the larger end of the first part across the smaller end of the second part, and having an opening from one part to the other that is also of 20 generally trigonal form and of less area than the area of said smaller end of the second part.

7. In tone developing apparatus, for sound 25 reproducing units, having a duplex tone chamber, an analyzing tone portal intermediate the two parts having substantially

flat side walls presenting projecting corner pieces arranged vertically in pairs.

8. In tone developing apparatus, for sound 30 reproducing units, having a duplex tone chamber, an analyzing tone portal intermediate the two parts comprising a centrally arranged opening increasing progressively 35 in width by a series of definite steps.

9. In tone developing apparatus, for sound 35 reproducing units, having a duplex tone chamber, an analyzing tone portal intermediate the two parts comprising a centrally arranged opening of irregular configuration 40 with the depth of the opening gradually decreasing from the top to the bottom and with the width of the opening gradually increasing.

10. Tone developing apparatus for sound 45 reproducing units comprising the combined tone chambers 10 and 20 both trigonal in longitudinal cross section having the intermediate tone analyzing portal 21 formed in resonant material, substantially as illustrated and described.

IRVING KIMBALL.
